(57) **CLAIM**

The ornamental design for a beverage container floatation device, as shown and described.

DESCRIPTION

FIG. 1 is an isometric view of a beverage container floatation device according to the present design; FIG. 2 is a side view thereof (the view from any side being identical);

FIG. 3 is a top view thereof;

FIG. 4 is a bottom view thereof; and,

FIG. 5 is an isometric view thereof showing how a beverage container would fit therein.

In FIGS. 1 and 3, the broken lines depict portions of the beverage container floatation device that form no part of the claim; and in FIG. 5, the broken lines depict use environment elements which form no part of the claim.

1 Claim, 5 Drawing Sheets(56)
